UNITED STATES PATENT OFFICE.

JOHN H. ROOK, OF JONESBOROUGH, INDIANA.

STEAM-INSPIRATOR.

SPECIFICATION forming part of Letters Patent No. 269,718, dated December 26, 1882.

Application filed November 2, 1882. (Model.)

To all whom it may concern:

Be it known that I, JOHN H. ROOK, a citizen of the United States, resident at Jonesborough, in the county of Grant and State of Indiana, have invented a new and valuable Improvement in Steam-Inspirators; and I do hereby declare that the following is a full, clear, and exact description of the construction and operation of the same, reference being had to the annexed drawings, making a part of this specification, and to the letters and figures of reference marked thereon.

Figure 1 of the drawings is a side view of my steam-inspirator. Fig. 2 is a vertical sectional view of the same, and Fig. 3 is a detail view of the part A.

This invention has relation to injectors for steam-boilers; and it consists in the construction and novel arrangement of a two-way steam-chest, the double-nozzle casting, and transverse connecting pipe or way, the connected overflow-valve and steam-valve, and the general combination, with these parts, of pipes and valves, all as hereinafter set forth.

In the accompanying drawings, the letter A designates a two-way steam-chest, in the division-wall *a* of which is formed a valve-seat, *b*, to receive a valve, *c*, whereof the stem *d* is threaded and works in a threaded plug, *e*. The stem *d* is provided with a crank-arm, *a'*. The ends of the steam-chest are cylindrical in form, and are designed to receive the upwardly-projecting cylinder ends *b'* of the steam-caps *B*. Each cap *B* is formed with an exterior shoulder, *c'*, at the base of the cylinder end *b'*, a wrench-seat, *d'*, a connecting-thread, *e'*, and a chamber-wall, *f*, which is designed to project within the chamber of the nozzle-casting.

In the steam-cap is provided a small aperture, *g*, which is axially arranged with reference to the cylinder end *b'*, and in said cylinder end is formed a lateral opening, *g'*, whereby communication is established with the steam-chest. The steam-caps connect the steam-chest to the double-nozzle casting *C*, which is cored out to form two nozzle-chambers, *D* and *D'*, two water-chambers, *h* and *h'*, below the same, respectively, and the nozzles *k* and *k'* extending into the chambers *D* and *D'* toward the jet-openings *g* of the steam-caps. A transverse pipe or way, *E*, connects the chamber *h*

of the first branch of the casting to the chamber *D'* of the second branch, as shown in the drawings. In this construction, when the steam-caps are connected to the casting the nozzles *k* and *k'* project within the surrounding walls *f*, which project from the steam-caps within the chambers *D* and *D'*. An opening, *l*, is made in the side wall of the chamber *D*, and a pipe, *F*, from the well or reservoir of water is here connected to said chamber *D*.

G represents the steam-pipe, leading from the boiler to the steam-chest *A*. This pipe *G* is provided with a throttle-valve, *m*.

H represents an overflow or waste spout, which is connected to the first branch of the double-nozzle casting, and is provided with a turning-valve, *p*, to which is connected an operating-lever, *K*, to which is pivoted the lower end of a connecting-rod, *R*, the upper end of which is pivoted to the crank-arm *a'* of the stem of the steam-valve *c*. The pivot or wrist pin of the crank-arm passes through a slot, *s*, of the connecting-rod, which is of sufficient length to allow the valve *p* to move or turn a short distance—about three eighths of an inch in the usual constructions—before the steam-valve commences to move.

To the second branch of the nozzle casting is connected a union-pipe, *L*, which is connected to the water-pipe *P*, leading to the boiler. The union-pipe *L* is provided with a water-cock, *t*, and a check-valve, *v*, as shown in the drawings. When the upwardly-projecting ends of the steam-caps are in engagement with the cylindrical ends of the steam-chest the closed nuts *N* are applied to the threaded ends of said steam-caps and turned to secure the caps firmly to the steam-chest.

In order to start the injector, the throttle-valve *m* being closed, open the overflow-valve *p* by means of its lever *K*, which, being connected to the crank-arm *a'*, will close the steam-valve *c*, shutting off the steam from the second branch of the injector, but leaving the way open to the first branch. Now open the steam throttle-valve *m*, and the steam will pass through the steam-chest, as indicated by the darts on the left-hand side, and through the jet-aperture *g* in the steam-cap on this side, through the nozzle *k*, forming a vacuum in the chambers surrounding said nozzle and in the

adjoining water-pipe F, so that the water flows from the well or reservoir through the nozzle k, condensing the steam and escaping at the overflow H. Close the overflow by moving the valve-lever K upward. This movement of the lever opens the steam-valve e, and the steam admitted to the right-hand passage of the steam-chest passes forcibly through the jet-aperture g in the steam-cap on this side into the nozzle-chamber D', where it meets the water which is conducted into said chamber from the lower portion of the first branch by the transverse pipe or way E. By means of the steam-jet the water is moved forcibly through the nozzle k', and the steam being condensed, it escapes through the water-cock t. This cock is now closed by means of its handle, and the water passes through check-valve r to the boiler. The nozzles being cast in the chambers of the body or main casting, are secure and firm in position, and cannot leak.

Having described this invention, what I claim, and desire to secure by Letters Patent, is—

1. The combination, with the double-nozzle casting and a two-way steam-chest having a

valve, of the steam-injector caps having upwardly-projecting ends passing through cylindrical ends of the steam-chest, and closed nuts securing the same in position, substantially as specified. 30

2. An injector having a two-way steam-chest and steam-valve therein, a double-nozzle casting and steam-jet caps connected thereto, a transverse connecting-way and overflow-valve, and a lever secured to said overflow-valve and connected to the crank-arm of said steam-valve, substantially as specified. 35

3. The combination, with the double-nozzle casting C, and its transverse way E, and the two-way steam-chest A, and its valve e, of the steam-caps B, having the jets g, the overflow H, its valve p, valve-lever K, and connecting-rod R, the union L, and water-cock t, substantially as specified. 40

In testimony that I claim the above I have hereunto subscribed my name in the presence of two witnesses.

JOHN H. ROOK.
